J. VON TRÜMBACH,

By *Johnnie* *ATY.*

UNITED STATES PATENT OFFICE

JOHANNES VON TRÜMBACH, OF DUSSELDORF-OBERKASSEL, GERMANY

DRAWING FRAME WITH PASSAGES FOR USE ON SPINNING MACHINES

Application filed March 2, 1929, Serial No. 344,086, and in Germany August 23, 1928.

The invention relates to an improved nipper for use in a drawing apparatus for spinning machines for co-operating with a lower drawing cylinder arranged between a pair of feed cylinders and a pair of delivery cylinders.

The objects of the invention are to prevent the accumulation of fibres and consequent prevention of the complete straightening out and stretching of the fibres which occur when the usual loose light top rollers are used and also to provide for more weight than can be applied with the usual top rollers of small diameter, a heavy weight being desirable particularly with coarse feeds.

It is also the object of the invention to attain the above desirable results with the aid of a nipper of simple construction of few parts not likely to impede the operatives in their work or to require undue attention.

With the above objects in view the invention consists in the novel construction, combination and arrangement of parts herein-after referred to and defined in the appended claims.

In the accompanying drawings:

Figure 1 is a side view of one form of nipper according to the invention shown applied to a drawing cylinder, between pairs of feed and delivery cylinders, which are only indicated diagrammatically, other parts of the drawing frame being omitted as well known in the art and not necessary to make the present description clear.

Figure 2 is a sectional end view of the nipper, the section being taken on II-II, Figure 3.

Figure 3 is a plan of the nipper.

Figure 4 is a side view half in section on IV-IV, Figure 3.

In the drawings *a*, *a'* are the delivery cylinders and *b*, *b'* the feed cylinders, *c* is an under drawing cylinder placed between the pairs of cylinders *a*, *a'* and *b*, *b'* and *d* is the nipper in position over the drawing cylinder *c*.

The pressure surface of the nipper *d* consists of a plurality, for example, two, small rollers *g*, *g'* provided with frictional peripheries, for example, as indicated by the plain roller *g'* in Figures 3 and 4, they may

be smooth, covered with leather or other frictional material as known in the art, or as indicated by the roller *g* in Figures 3 and 4, they may be provided with grooves of any conventional type, or any equivalent grooving capable of providing the necessary frictional surface. The rollers *g*, *g'* have their end journals *m*, *m* mounted so as to have a certain amount of play in slots *h*, *h* in end pieces *n*, *n* of the body *o* of the nipper *d*, the end pieces *n*, *n* being conveniently secured to the body *o* by screws *l*, the heads of which form journals for the nipper.

Interdriving means are provided between the rollers *g*, *g'*, for example, such rollers have driving bearing surfaces *i* which press against rotating rings or friction wheels *k* running on ball bearings *p*. By this means the rotary movement and peripheral speed of one roller are positively imparted to the other roller. Neither of the two rollers can make a false movement relatively to the other and so lead to the accumulation of the fibres, and render more difficult or entirely prevent, the complete straightening out and stretching of the fibres. The drawing process will proceed without interruption owing to the positive uniform rotary movements and peripheral speeds of the two rollers *g*, *g'*, which is of the greatest importance in the process of spinning.

If the rollers *g*, *g'* are provided in a known manner with fine annular or screw-threaded grooves, the combing action of the fine ribs between the annular or screw-threaded grooves will result in the loosening and separation of the bundle of fibres of the rough yarn, spread over a distance equal to the distance between the rollers *g*, *g'*, this distance being approximately equal to the average length of the fibres. The fibres of the rough yarn or bundle of fibres, which are previously tightly held together, are so effectively loosened and shaken up that the single fibres are enabled and assisted to pass smoothly through the fine annular or screw-threaded grooves in the rollers *g*, *g'* and thus a high degree of drawing is obtained. This is a great advantage of the drawing frame according to the invention.

The weight of the nipper assists the drawing cylinder to drive the rollers g , g' and influences the drawing process of the rough yarn. The weight may be apportioned as desired, without increasing the diameter of the rollers g , g' or their distance away from the contacting parts of the pair of delivery cylinders a , a' or for enlarging the force drawing field.

10 The nipper can be inserted into and removed from the existing bearings in the same way as the known loose running top rollers. The heads of the screws l act as journals, so that it is unnecessary to make any mechanical alterations, while it is easily handled.

15 I claim:

1. For use in a drawing apparatus for spinning machines, a nipper movably mounted above a drawing cylinder including a pressure jaw for bearing on the yarn said pressure jaw presenting pressure surfaces, for co-operating with said drawing cylinder, comprising freely mounted rollers provided with frictional peripheral surfaces and interdriving means between said rollers, substantially as and for the purposes hereinbefore set forth.

2. For use in a drawing apparatus for spinning machines, a nipper adapted to be mounted movably above a drawing cylinder and comprising a pressure jaw provided with journals and slotted bearings at its ends and rollers freely mounted in said bearings, said rollers constituting pressure surfaces and having frictional peripheries to co-operate with said drawing cylinder substantially as and for the purposes hereinbefore set forth.

3. For use in a drawing apparatus for spinning machines, a nipper comprising a body having end journals, and elongated bearings, rollers freely mounted in said bearings to serve as pressure surfaces, said rollers having grooved peripheries, wheels freely mounted at the ends of said body and having a frictional driving connection with the said two rollers, to thereby provide a driving connection between said rollers.

In testimony whereof I have signed my name to this specification.

JOHANNES VON TRÜMBACH.
